UNITED STATES PATENT OFFICE.

CARL LANGE, OF NEU WEISSENSEE, NEAR BERLIN, GERMANY.

COMBINED SEAT AND CANE.

SPECIFICATION forming part of Letters Patent No. 393,160, dated November 20, 1888.

Application filed March 2, 1887. Serial No. 229,466. (No model.) Patented in Belgium January 31, 1887, No. 75,944; in France June 6, 1887, No. 181,048, and in Austria-Hungary June 21, 1887, No. 4,751 and No. 25,356.

To all whom it may concern:

Be it known that I, CARL LANGE, of Neu Weissensee, near Berlin, in the Kingdom of Prussia, and German Empire, have invented 5 a new and useful Combined Seat and Cane, of which the following is a specification, reference being had therein to the accompanying drawings, no patents being obtained by me anywhere for this invention, save in Austria- 10 Hungary, No. 4,751 and No. 25,356, dated June 21, 1887; Belgium, No. 75,944, dated January 31, 1887; France, No. 181,048, dated June 6, 1887.

My invention relates to a combined seat and 15 cane, the handle, the upper and lower parts of which can be dismounted, whereby the upper part forms, when taken to pieces, a frame upon which is tightened a net.

Figure 1 shows the combined seat and cane 20 in a longitudinal section; Fig. 2, the upper part when the cane is dismounted arranged as seat in plan; Fig. 3, the same in a cross-section on line $y's$; Fig. 4, the lower part of the cane with the ferrule and the spring g . Fig. 25 5 represents the handle. Fig. 6 shows an iron leg-disk, such as may be fastened on the legs of the frame. Fig. 7 shows a cross-section through the combined seat and cane on line $a\beta$; Fig. 8, a cross-section. Fig. 9 is a front 30 view of the lower part of the cane with spring g caught in the opening i of leg b . Fig. 10 is a front view of a portion of one of the legs.

The exterior shape of this combined seat and cane does not differ in any way from a 35 common cane. It can be dismounted in an upper and lower part. The former is made of gas-pipe and hoop-iron, and consists of three single legs, $a b c$, connected to each other by a common trunnion, d , a little below the 40 middle of the legs. On the upper end of this part there is tightened, by means of little screws, a net, e , made of strong laces. When using the cane, this net e will serve as a seat after said upper part has been dismounted 45 into a frame, Fig. 2. To prevent the frame from sticking or sinking into the soft ground, there are fixed on the lower end of the legs little disks, Fig. 6, which oppose a larger surface to the pressure. The three legs of the 50 upper part may be pressed together in such a

way as to form a part of cane that shows a round cross-section, Fig. 3. On the upper end of this part (lettered O) thus pressed together there will be fixed, in case the combined seat and cane is to be used as a cane, the 55 lower part, U , with ferrule, Figs. 1 and 4. This latter is composed of a wooden stick and a thin walled tube, n , arranged upon it, which, when the legs $a b c$ have been pressed together, fits closely on over the leg ends of the upper 60 part, thus keeping them together. In order to prevent the lower part, U , falling off the upper part, there is fixed on the lower part a spring-catch, g , that is placed into one of the 65 hollow legs, b , and catches into an opening, i , in the same, Fig. 9, in such manner that the upper part, O , and the lower part, U , are connected to each other. The net fastened to the upper part will, after the combined seat and cane has been put together, be placed in the 70 handle k . This handle is hollowed out and can be taken off the upper part, O , or fixed on it by means of the bayonet-closure l . The hollow handle is just large enough to receive the leg-disks f , Fig. 6, also, and it may be 75 given any other shape different from the present one. By pressing the spring-catch g the lower part, U , can be removed from the upper part, O .

Figs. 8 and 10 show the manner in which 80 the trunnion d is inserted into the legs $a b c$. This is effected by boring a hole, z , into each of the legs near the hole x for one arm of the trunnion d . The hole z , which is somewhat 85 larger than the balls of the trunnion, is provided with a screw-thread and communicates with the boring x , so that the total boring in the band shows an egg shape. The trunnion, with a ball, is introduced through the hole z and moved until its arm is held in the hole x . 90 Then the hole z is closed by a short pin, z' , fitted with an exterior thread. Thus the trunnion is tightly secured to the one leg, and in the same way it is inserted into the other legs. This new combined seat and cane shows very 95 important advantages when compared to the well-known camp-cane. In the first place it does not differ in the least in its exterior shape from a common cane, its weight also being only a very little more than that of a common 100

cane. There are further adapted to it all the necessary parts requisite to offer a comfortable seat.

What I claim, and desire to secure by Letters 5 Patent of the United States, is—

1. A combined seat and cane composed of upper part, O, consisting of the three legs *a b c*, under part, U, and handle *k*, as set forth, the under part, U, having a thin walled tube 10 fitting loosely over the ends of the legs *a b c*, and the spring *g*, catching into the opening *i* in the hollow leg *b*, substantially as described.

2. In a combined seat and cane having upper part, O, consisting of the three legs *a b c*, under part, U, and handle *k*, as described, 15 the disk *f* on the lower end of legs *a b c*, substantially as described.

In witness whereof I have hereunto set my hand in presence of two witnesses.

CARL LANGE.
